UNITED STATES PATENT OFFICE.

GOLDWIN SMITH, OF TAMPA, FLORIDA.

MECHANICAL BASEBALL GAME.

Application filed August 20, 1927. Serial No. 214,317.

The invention relates to improvements in mechanical base ball games of the kind described in my application for a United States Patent, Serial Number 189,948, filed 5 May 9, 1927.

The objects of the invention are to provide simple, efficient, practical, economical and durable means, whereby the game of base ball may be simulated by players thereof while the latter are indoors; to provide means adapted to "bat" or strike the ball, during playing of said game, for the purpose of imparting motion of said ball toward a stationary field having pockets to receive 15 the ball which effects the final score of said players; to provide means whereby skill of the players in playing said game is acquired by practice; to provide means whereby the most skillful player is adapted to receive credit for the highest score and, therefore, is the successful participant of the several players of said game.

Other objects will be apparent from the hereinafter description.

25 The invention consists in the combination of the various parts, the arrangement of the elements comprising the game, and in the details of the construction, as set forth and claimed.

30 In the drawings:

Fig. 1 is a plan view of the invention with parts broken away;

Fig. 2 is a section taken on a line corresponding to 2—2 in Fig. 1;

35 Fig. 3 is an enlarged view showing a modified form of the batter;

Fig. 4 is a section taken on a line corresponding to 4—4 in Fig. 1, with parts broken away;

40 Fig. 5 is an enlarged longitudinal sectional view showing the spout in full lines inclined upwardly and showing the spout in dotted lines extending downwardly for dropping the ball;

45 Fig. 6 is a section taken on a line corresponding to 6—6 in Fig. 1, with parts broken away;

Fig. 7 is a plan view showing a modified form of the batter;

50 Fig. 8 is a plan view of the track;

Fig. 9 is a side elevation of the invention; and

Fig. 10 is a section taken on a line corresponding to 10—10 in Fig. 1.

55 In the preferred construction of the in-

vention I provide the circular table or drum 1 comprising the top 2 and the bottom 3 secured in spaced apart relation, as by the turnbuckles 4 threaded to the inner ends of the threaded bolts 5 and 6, having their outer ends, respectively, suitably secured in the outer edges of the top and bottom, whereby the top and bottom are maintained in adjusted stationary position with relation to each other. The inner ends of the rods 4 are secured to the center of the bottom 3 and have their outer ends slidably engaging the lower side of the top 2 to effect stability of the top 2, whereby the centrally disposed perforations 7 and 8 are maintained in vertical alignment with each other.

From the hole 7 the top 2 slopes upwardly and outwardly, whereby a sphere or ball is adapted by the force of gravitation, to be carried from any point on the top toward the hole 7.

Rotatably mounted in the hole 8, of the bottom 3, is the spindle 9 having fixed to its upper end 10, the mechanical batter 11 which projects through the hole 7 in the top 2, with its feet adjacent the inner edges of the top surrounding the hole 7. The batter preferably is made to simulate a ball player in the act of batting.

Fixed to the lower end 12, of the spindle 9, is the bevel gear 13 meshing with the bevel gear 14 fixed to the inner end 15 of the shaft 16 rotatably mounted in suitable bearings in the U-shape supports 17 suitably fixed to the support 18 suitably fixed to the inner sides 19 of the semi-spherical container 19' having its round side 20 positioned downwardly.

Suitably fixed to the outwardly projecting flange 21, extending parallel to the top 19', of the container, are a plurality of legs or supports 22, having fixed to their lower ends 23, the rollers 24 which are adapted to roll in the circular track 25, whereby the container, with the parts fixed to it, may be manually rotated. The track 25 may be laid upon the ground, or secured to the flooring of the building in which the game is assembled for play.

Fixed to the outer protruding end 26 of the shaft 16 is the manually operative crank 27 for purposes hereinafter fully explained.

Suitably secured to the spindle 9, within the internal gear 13', fixed to the bottom 3 of the table, is the external pinion gear 28

meshing with the external pinion gear 29 rotatably mounted on the stud 30 having its upper end 31 suitably fixed in the top 32 of the internal gear 13'.

5 The internal gear 13' is fixed to the bottom 3, as by the bolts 33. The spindle 9 is received by the hole 34, centrally disposed in the top 32 of the internal gear. The collar 35 is fixed to the spindle adjacent the upper 10 side 36 of the bottom 3 of the table 1.

The spindle 9, is maintained against downward movement, and its lower end 12 is maintained against lateral movement, as by the lower end being rotatably mounted in 15 the bearing 37 in the upper end of the vertical staff 38 having its lower end 39 securely bolted to the support 18.

The teeth 40, of the internal gear 13', are in continuous mesh with the teeth 41 of the 20 pinion gear 29, the teeth of which are in continuous mesh with the teeth 42, of the pinion 28, whereby manual rotation of the crank 27 simultaneously imparts rotatable movement to the mechanical batter or striking 25 element 11 and the table 1.

The gearing connections, just previously explained, are for the purpose of rotating the mechanical batter 11 in a direction opposite to the direction of rotation of the table 1, whereby when the ball, or sphere 1', is positioned at any point upon the top 2, of the table 1, and the crank 27 is rotated at a rate, unadapted by the centrifugal force, to cause the sphere to move outwardly and 30 off of the table, the ball is adapted to roll down the sloping top 2, toward the mechanical batter 11, and the bat 43, secured to the hand 44 of the batter, is caused to strike the ball and thereby drive it outwardly of 35 the table.

If desirable, a plurality of bats or striking elements 43 may be attached to the batter 11. The resilient projections 11' may be fixed to the bats as shown in Fig. 7 to effect 45 greater resiliency when a bat contacts the ball.

Surrounding the table 1, and positioned with its inner edge 46 adjacent the outer edge 47 of the table 1, and in horizontal 50 alignment therewith, is the stationary circlet or field 48 having the pockets 49, 50, 51, and 52 positioned at the outer edge 46' of the circlet and separated by 90°, circumferentially of the field, to represent home plate, first base, second base, and third base, respectively, of the invention. The pockets are in a horizontal plane.

Intermediate the pockets 49 and 50, 50 and 51, 51 and 52, 52 and 49, are the ridges 53, 60 54, 55, and 56 which are equi-distant elevated from the position of the pockets 49, 50, 51 and 52. The upper surface 57, of the circlet intermediate the ridges slope downwardly toward the adjacent pockets, whereby a sphere or ball positioned at any point be-

tween the ridges 53 and 54, 55 and 56, and 70 56 and 53 is adapted to be carried, by the force of gravitation, into the one of the pockets which is between the ridges between which the ball is positioned.

The ridges 54, 55, and 56 are spaced equidistant from the adjacent pockets, but the ridge 53 is positioned in closer proximity to the pocket 49 than to the pocket 50, to effect greater difficulty of a player in causing the 75 ball to enter the hole 49.

The circlet 48 is maintained in adjusted position, with relation to the table 1, as by the spaced apart arms 57' (which extend under and support the circlet) having their 80 outer ends 58 secured to the inner surface 59 of the guard 60. The spacers 61 and 62 are between the guard and the end 58 of the arms. The thickness of the spacers determines the position of the pins 63 in the arms 85 whereby the position of the circlet with respect to the outer edge of the table is adjusted.

The guard 60 comprises the vertical body 64 having the inwardly extending flange 65 90 integrally formed with its upper end 66 and extending inwardly thereof. The inner edge 67 of the flange is positioned slightly outwardly of the outer edge 46' of the circlet. The circlet is adapted to be removed from 95 the invention without the necessity of disturbing the guard 60 or the table 1. The lower edge of the guard is suitably secured to the support 18.

Surrounding the circlet 48, except at the 100 pockets, and having its top 68 formed of pickets 69 and protruding above the top 57 of the circlet, is the fence 70 having its lower edge 71 secured to the circlet, whereby when, due to rapid rotation of the table 1, or as 105 the result of a heavy impact of the bat 43 with the ball, the latter is adapted to be driven outwardly from the table 1, over the circlet 48 and in contact with the fence. An important object when playing the game is 110 to manipulate the crank 27 so that the ball will be caused finally to enter the pocket 49 which counts twenty points to the player's score. The entrance of a ball into the pockets 50, 51, and 52, respectively, counts fifteen, 115 ten and five points to the player's score.

The fence 70 preferably is made of sheet rubber which is adapted, under certain circumstances, to cause the ball to rebound onto the circlet 48 and roll into one of the 120 pockets 49, 50, 51 or 52.

When, for any reason, the ball is driven from the table 1 and over the fence 70 it is adapted to contact with one of the pendants 72 hingedly connected with the flange 65, and is diverted downwardly, between the outer edge 46' of the circlet and the body 64 of the guard 60, upon the downwardly and inwardly inclined board 73 from where the ball is adapted to roll into the trough 74. 130

The player gains no points to increase his score when a ball is driven over the fence 70. The trough 74 is inclined downwardly toward the bin 75 and communicates therewith whereby the ball is carried, by the force of gravitation, from the trough into the bin which is suitably secured to the inner side of the container 19'. The ball may be removed from the bin through the opening 76 in the container.

If desirable, advertisements may be attached to the outer sides of the pendants 74.

Positioned directly underneath the pockets 49, 50, 51 and 52, respectively, are the baffle plate counters 77. The purpose of the counters is, through operative connection with suitable counter mechanism, to automatically register by contact of the ball with each plate, whereby the number of the plates positioned under the holes 49, 50, 51 and 52 will be decreased in the order named. Or any suitable counter mechanism may be utilized for the purposes intended.

For the purpose of enabling the players to conveniently position a ball upon the top 2, of the table 1, the mechanical ball ejector 78 is connected with the top of the flange 65. The ejector may consist of spring blade 79 having its outer end 80 fixed to the top of the flange 65, and having the concave scoop 81 fixed to its inner end 82 whereby normally, when the scoop contains no ball the spring 79 automatically causes the scoop to move upwardly from the table 1 into the position shown in Fig. 2. When it is desirable to place a ball upon the top of the table, the ball is dropped into the scoop. The tensional strength of the spring 79 is such that the weight of the ball causes the scoop to be lowered into the position represented by the dotted lines in Fig. 5, whereby the ball is permitted to roll out of the scoop onto the table.

Each of the pockets 49, 50, 51 and 52, comprise the trap-door 83 having its outer end 84 hingedly connected, by the pin 85, to the boss 86. The inner end 87 of the door is positioned in the recess 88 in the circlet.

Adjacent the edges 89 and 90 of the door are the plates 91 and 92 fixed to the guard and extending at right angles to the horizontal plane of the circlet to guide the ball from the circlet onto the door. A ball which enters upon the door is permitted to fall through the pocket onto the board 73. The coiled spring 93 normally maintains the door in its closed position, but the weight of a ball upon the door is adapted to overcome the tension in the spring to permit the door to pivot downwardly to permit the ball to fall into the trough.

In Fig. 3 I show a modified form of the batter comprising the coil spring 94, fixed to the spindle 9, having the bat 43 secured

thereto. The head 95 is secured to the spring 94 which may be clothed to represent a ball player.

Suitable figures, as the spectators 95 and an umpire 96, may be fixed to the fence, or to the outer edge of the circlet, and with their heads protruding above the top thereof. And points may or may not be given to the player who manipulates the crank 27 in such a manner as to cause the ball to strike the figures.

It is desirable to position the crank 27 and the opening 76, in the container 19', in juxtaposition for the reason that an important advantage of the invention is that various players may seat themselves around the container and after one of the players has completed his turn of manipulation of the crank 27, the container may be rotated in the track 25 to position the crank in close proximity to the player whose turn is the next succeeding one to manipulate the crank.

If, desirable, suitable mechanism may be provided for automatically delivering three, or other quantities, of balls from the bin upon the insertion of a predetermined coin in the mechanism. The playing of three balls may represent an inning for one player and, with the usual nine innings comprising a game of base ball, playing a total of twenty-seven balls will be required for each player to complete a game.

However, it is quite apparent that the game may be played by various and numerous other rules and regulations which may be devised from time to time by the manufacturers, sellers and users of the game.

At the completion of a game the points gained by a player are added and his winning, and being the successful participant in the game depends upon whether he has earned a greater number of points than other players.

If desirable, a coin operated apparatus may be suitably positioned and having connection with the mechanism of the invention whereby it is necessary for a player to deposit a coin in the apparatus to play the game. Moreover, a suitable lighting system may be incorporated in the invention.

After the ball is positioned upon the upper surface of the top 2 of the table, the skill of the player in operating the crank 27 to rotate the table 1 at the proper speed, and in causing the batter 11 to drive the ball determines to a great extent whether the ball will be forced upon the circlet 48 and into one of the holes 49, 50, 51 or 52, or whether it will be forced over the fence.

It is now apparent that I have invented a highly desirable and interesting game for the purposes intended and which may be the means for providing enjoyable recreation for players who desire to simulate playing the national game of base ball.

It is readily apparent that I have devised a novel and useful structure, which embodies the features of advantage enumerated as desirable in the statement of the invention and the above description, and while I have, in the present instance, shown and described a preferred embodiment thereof which will give in practice satisfactory and reliable results, it is to be understood that the same is susceptible of modification in various particulars without departing from the spirit or scope of the invention or sacrificing any of its advantages.

What I claim as new and desire to secure by Letters Patent is:

1. In a device of the class described, the combination with a ball, of rotatable means, a stationary field surrounding said means and having a plurality of pockets therein, manually operative means to rotate said first mentioned means, and movable means adapted to strike and drive said ball from said first mentioned means toward said field, substantially as and for the purposes specified.

2. In a device of the class described, the combination with a ball, of rotatable means, a field surrounding said means and having pockets therein, manually operative means to rotate said first mentioned means, and means adapted to strike and drive said ball from said first mentioned means toward said field, substantially as and for the purposes specified.

3. In a device of the class described, the combination with a ball, a rotatable table, a field surrounding the table and having a plurality of pockets therein, manually operative means to rotate said table, and means adapted to bat said ball toward said field, substantially as and for the purposes specified.

4. In a device of the class described, the combination with a ball, of a rotatable table, a stationary circlet surrounding the table and having a plurality of equidistant spaced apart pockets adjacent thereto, manually operative means to rotate the table, and means adapted to bat said ball toward said pockets, substantially as and for the purposes specified.

5. In a device of the class described, the combination with a ball, of a rotatable table, a resilient striking element at the centrally disposed top of said table, a stationary field surrounding the table and having a plurality of pockets therein to receive said ball, a resilient fence partly surrounding said field, manually operative means to rotate the table and said element to drive said ball toward and into said field, whereby skill of the players of said game determines whether said ball is received by one of said pockets, or driven over said fence.

6. In a device of the class described, the

combination with a ball, of a rotatable table, a striking element at the top of said table, a field surrounding said table and having a plurality of pockets therein to receive said ball, a circlet in said field adjacent said table, said pockets being adjacent the outer edge of said circlet, a fence surrounding said circlet except at points adjacent said pockets, manually operative means to rotate the table and said element to drive said ball toward and into said field, whereby the skill of the players of the game determines whether said ball is received by one of said pockets or driven over said fence.

7. In a device of the class described, a rotatable table, a field surrounding said table and said field having a plurality of pockets therein, a fence in said field, manually operative means to rotate the table, and means centrally disposed of said table and adapted to be rotated in a direction opposite from the direction of rotation of said table.

8. In a device of the class described, the combination with a ball, of a rotatable table, a stationary field surrounding said table and said field having a plurality of pockets therein, a resilient fence around said field except at the location of said pockets, manually operative means to rotate said table, and rotatable means centrally disposed of said table to impart movement to said ball toward said field.

9. In a device of the class described, a rotatable table, a striking element adjacent the upper surface of said table, a stationary circlet surrounding said table and having a plurality of pockets adjacent thereto, the surface of said circlet adjacent said pockets sloping downwardly toward said pockets, and manually operative means to rotate the table and to impart movement to said element, substantially as and for the purposes specified.

10. In a device of the class described, rotatable means, a mechanical batter adjacent the upper surface of said means, a field surrounding said means and having a plurality of pockets therein, the surface of said field adjacent said pockets sloping downwardly toward said pockets, and manually operative means to rotate said first mentioned means and said batter, substantially as and for the purposes specified.

11. In a device of the class described, a rotatable table, a mechanical batter adjacent the upper surface of said table, a stationary field surrounding said table and having a plurality of pockets therein, the surface of said field adjacent said pockets sloping downwardly toward said pockets, and manually operative means to rotate said table and said batter, substantially as and for the purposes specified.

12. In a ball game device of the class described, a rotatable table, a batter posi-

- tioned above said table, a stationary field surrounding said table and having a plurality of pockets therein representing home plate, first base, second base and third base, 5 the surface of said field sloping toward said pockets, and manually operative means to rotate the table and said batter, substantially as and for the purposes specified.
13. In a ball game device of the class described, a rotatable table, a batter positioned above said table, a stationary field surrounding said table and having a plurality of pockets therein representing home plate, first base, second base and third base, the surface 15 of said field sloping toward said pockets, and manually operative means to rotate the table and said batter in opposite directions, substantially as and for the purpose specified.
14. In a game, the combination with a ball, 20 of a rotatable table, means to automatically drop said ball upon said table, a rotatable batter mounted above said table, a circlet having four pockets adjacent its outer edge to receive said ball, said pockets representing 25 home plate, first base, second base, and third base, the surface of said circlet sloping downwardly toward said pockets, a return bin for said ball, means to convey the ball from said pockets to said bin, manually operative means to rotate the table and said batter, whereby said ball is adapted to be contacted by said batter and received by 30 one of said pockets, substantially as described.
15. In a device of the class described, the combination with a movable means, of a rotatable means, a field surrounding said last mentioned means, registration means in combination with said field, a striking element, 35 manually operative means adapted to rotate said rotatable means and impart movement to said element whereby said movable means is adapted to communicate with said registration means.
16. In a ball game device, the combination 40 with a ball, of a rotatable drum having a top sloping downwardly toward the center thereof, and said top having a perforation therein, a circlet surrounding said drum and having a plurality of pockets adjacent thereto representing home plate, first base, second base, and third base, the upper surface of 45 said circlet adjacent said pockets sloping downwardly toward said pockets, a sectional resilient fence around said circlet, a guard surrounding said circlet, batting means projecting upwardly through said perforation, 50 manually operative means to rotate said drum and said batting means whereby when said ball is placed upon the top of said drum, being rotated at a predetermined velocity, 55 said ball is adapted to roll toward said perforation and be driven by said batting means upon said circlet and carried into one 60 of said pockets, and when the rotatable speed 65 of said drum is increased said ball instead of entering one of said pockets is adapted to be forced by said batting means over said fence.
17. In a base ball game, a track, a semi-spherical container, a support fixed to the sides of said container, a vertical staff fixed to said support and having a bearing therein, 70 a circular table having a top and bottom having centrally disposed holes therein, a spindle extending through said holes and having its lower end rotatably mounted in said bearing, a batter fixed to the upper end of said spindle and protruding through the hole in the top of said table, a manually 75 operative crank, gearing connections between said crank and said spindle and said table, whereby rotation of said crank is adapted to rotate said batter and said table in opposite directions, a circlet around said 80 table and having a plurality of pockets adjacent thereto, the surface of said circlet adjacent said pockets sloping downwardly thereto, a resilient fence around said circlet except at said pockets, a guard surrounding 85 said circlet and spaced apart therefrom, whereby a ball driven from said table over said fence is adapted to drop between said guard and said circlet, a bin in said container, a trough under said pockets, and sloping 90 downwardly toward said bin, whereby balls driven between said circlet and said guard, and balls entering said pockets are received by said trough and directed to 95 said bin, a ball ejector comprising a spring pivoted to said guard, means at the inner end of said spring adapted to eject said ball after which said spring is adapted to move said means upwardly of said table, legs fixed to said container, and rollers fixed to 100 the lower ends of said legs and received by said track, substantially as and for the purposes specified.
18. In a base ball game, a track, a semi-spherical container, a support fixed to the sides of said container, a vertical staff fixed to said support and having a bearing therein, 110 a circular table having a top and bottom having centrally disposed holes therein, a spindle extending through said holes and having its lower end rotatably mounted in said bearing, a batter fixed to the upper end of said spindle and protruding through the hole in the top of said table, a manually 115 operative crank, gearing connections between said crank and said spindle and said table, whereby rotation of said crank is adapted to rotate said batter and said table in opposite directions. a circlet around said table and having a plurality of pockets adjacent thereto, the surface of said circlet adjacent said pockets sloping downwardly thereto, a resilient fence around said circlet except at said pockets, a guard surrounding 120 said circlet and spaced apart therefrom, whereby 125 130

- a ball driven from said table over said fence is adapted to drop between said guard and said circlet, trap-doors hingedly connected with said guard adjacent said pockets and
5 adapted normally to close said pockets, a bin in said container, a trough under said pockets and sloping downwardly toward said bin, whereby balls driven between said circlet and said guard, and balls entering
10 said pockets are received by said trough and directed to said bin, a ball ejector comprising a spring pivoted to said guard, means at the inner end of said spring adapted to eject said ball after which said spring is adapted to move said means upwardly of 15 said table, legs fixed to said container, and rollers fixed to the lower ends of said legs and received by said track, substantially as and for the purposes specified.

GOLDWIN SMITH.
